[57] CLAIM

The ornamental design for a line of bath accessory, as shown and described.

DESCRIPTION

FIG. 1 is a top, front, and right side perspective view of a bath accessory showing my new design as embodied in a wastebasket;

FIG. 2 is a front elevational view thereof, the rear being identical in appearance;

FIG. 3 is a left side elevational view thereof, the right side being identical in appearance;

FIG. 4 is a top plan view thereof;

FIG. 5 is a bottom plan view thereof;

FIG. 7 is a front elevational view thereof, the rear being identical in appearance;

FIG. 8 is a left side elevational view thereof, the right side being identical in appearance;

FIG. 9 is a top plan view thereof; and,

FIG. 10 is a bottom plan view thereof.
